WIRE WINDER

Raymond I. Renier, Los Angeles, Calif.

Application March 25, 1940, Serial No. 325,831

2 Claims. (CL 140—123)

This invention concerns a wire winding device operative to neatly wind one wire upon the straight portion of another wire, or the end portion of a wire upon itself at a point removed from its end.

Although this invention is useful in any mechanical vocation wherein wires are twisted together, the invention has particular usefulness for winding the ends of fish wires or leaders to form a loop to hold a fish hook and the like.

An object of this invention is to present a simple wire winder that is economical to manufacture and which can be easily carried about in a fisherman's pocket.

Another object is to provide a wire winder which is especially adapted to wind a thin wire neatly upon itself to form a loop.

Still another object is to provide a wire winder and cutter combined together, the winder being constructed for neatly winding an end of a small wire about itself to form a loop and the cutter being constructed to snip off the end of the protruding wire when the winding operation is complete.

Other objects, advantages and features of my invention will appear from the accompanying drawing, the subjoined detailed description, the preamble of these specifications and the appended claims.

Applicant is about to illustrate and describe one of the forms of his invention in order to teach one how to make, use and vend the same, but it is to be understood that the drawing and description thereof are not to limit the invention in any sense whatsoever, except as limited by the appended claims.

In the drawing:

Fig. 1 shows the invention in front perspective view.

Fig. 2 is a front elevational view.

Fig. 3 is a side elevational view.

Fig. 4 is a rear perspective view.

Fig. 5 shows a side elevational view of a modified form of the invention.

Fig. 6 is a front elevational view of a modified form.

The reference character 1 indicates the wire winder and the numeral 2, the wire to be wound upon itself to form a loop 3 to hold the fish hook

4. Although the principal use of the wire winder will be to form loops for fish line leaders, nevertheless, the invention is equally well adapted for winding two independent wires together and would be very useful to linemen, electricians,

cable splicers, wire fence constructors and repairmen in general.

The form of the invention shown in Figs. 1 to 4 inclusive, comprises a base element 5 of metal or other strong material having a turned up end or flange 6. The flange is shown as bent far enough over itself to form an acute angle with the base 5, but, however, such a sharp bead is not necessary for the flange may be at right angles or any other angle with the base 5. At the bend 7 of the base element, and at or near the center thereof, is a small hole 8; this hole being large enough to receive the end 2' of the wire. At the point 9 of the base, is provided a hole to accommodate the pivot rivet 10.

Upon the base element 5 is an element having the shank 11, finger grip portion 12 and tool end 13. Shank 11 has a hole 14 to receive a portion of the pivot rivet 10. These elements, base 5 and shank 11, are held permanently together by the head of the rivet and the hammered end thereof. So that the two elements will smoothly slide upon one another in scissor fashion, a washer 15 is provided as shown. When the flange 6 is bent at a sharp angle, the tool end 13 may have a small bevel at 16 so that the end 17 of the tool end can snugly hold the wire 2 against the bend of the flange. The wire length between the end 17 and bend of the flange acts as a bearing when the winder is rotated about the axis formed by this wire length.

Operation

The wire winder device has its parts arranged as shown in Fig. 2 before the wire is inserted. The end of the wire is first threaded through the small opening between the end 17 and the flange bend 7; should there be any difficulty in forcing the wire through the opening, the tool end 13 may be swung away from the flange and then replaced after laying the wire in place. Enough wire should be allowed to form the loop 3 at the desired size. The wire end is then threaded through the small hole 8. Fig. 2 shows the position of all factors just prior to beginning the winding operation. Each element 5 and 11 is provided with hardened steel inserts 18 which can be arranged concentrically for receiving a wire and cutting same when the inserts are separated.

To wind the wire neatly about itself, the loop 3 should be held by the left hand firmly near the winder. The right hand may now rotate the winder in the direction indicated by the arrow in Fig. 3. While winding, the winder should be

continuously urged toward the left hand so that the convolutions of the coil are neatly wound adjacent one another. When the winding operation is complete, the wire can be easily removed by first turning the tool end 13 away from the flange 6.

The modified form shown in Figs. 5 and 6 comprise superimposed shanks 20, 21 and 22 which are pivoted together by the rivet 23 in the manner shown. The shank 20 has one end thereof offset to form a handle 24, and the other end bent to form the flange 25. At the bend 26 of the flange, is provided a small hole 27 to receive an end of the wire to be wound.

The shank 21 has an offset handle portion 28 and a tool end 29 formed with a corner bevel 30. The bevelled portion and the bend of the flange form a tunnel 31 to receive the wire upon which is to be wound another wire or the end of the same wire.

The shank 22 is shorter than the others and has one end turned upwardly to form a flange 32 which can easily be gripped by the fingers of the operator. The other end of the shank has a tool end 33 constructed similarly to the tool end 29 of the shank 21. The lower corner of the tool end 33 is also bevelled to continue the tunnel formation 31 along the inner side of the bend of the flange 25. Inserts 34 of hardened steel are provided in the shanks 20 and 21 to cut wire as explained for the inserts 18. The shanks 21 and 22 are provided with turned stop elements 35 and 36 respectively.

This modified form of the winder operates in

the same manner as explained for the other form of the invention, except that an additional element is included. This additional element is the extra wire holder 22 for holding the wire against the flange 25 on the opposite side of the hole 27 from the wire holder 21. With the additional holder 22, the winding wire is more neatly wound upon the wire in the tunnel 31 and with greater ease than when the other form of the invention is used.

Having thus described my invention, what is claimed as new and desired to be secured by Letters Patent is:

1. In a wire winding device, a plurality of elongated elements pivoted together intermediate the ends thereof, all of said elements having wire contact ends and the other ends thereof forming a handle, a flange on the end of one of the elements with a hole to receive the wire to be wound, said other elements having means to engage the wire to be wound and hold it snugly against the flange on opposite sides of the wire hole.

2. In a wire winding device, a first shank having a handle at one end and a wire receiver at the other end, a second shank pivoted to the first shank, said second shank having a handle at one end and means at the other end for holding a wire snugly in a portion of the wire receiver, a third shank pivoted to said other shanks, said third shank having a handle at one end and means at the other for holding a wire snugly in another portion of the wire receiver.

RAYMOND I. RENIER.
